The ornamental design for a semi-conductor element with
terminal casing, as shown.

[**] Term: 14 Years

DESCRIPTION

[21] Appl. No.: 28,486

FIG. 1 is a perspective view of the front, top and right side
of a semi-conductor element with terminal casing showing
our new design;

[22] Filed: Sep. 16, 1994

FIG. 2 is a front elevational view thereof;

[30] Foreign Application Priority Data

FIG. 3 is a top plan view thereof;

May 23, 1994 [JP] Japan 6-14733

FIG. 4 is a right side elevational view thereof;

[52] U.S. Cl. D13/182; D13/146

FIG. 5 is a left side elevational view thereof;

[58] Field of Search D13/182; 174/52.4,
174/52.5; 257/690; 361/752, 798, 820

FIG. 6 is a rear elevational view thereof; and,

[56] References Cited

FIG. 7 is a bottom plan view thereof.
